CLOCK FACE

Richard A. Strong and Rosa M. Strong, Temple Hills, Md. (both % Air Force Institute of Technology, Wright-Patterson Air Force Base, Ohio 45433)

Filed Nov. 5, 1970, Ser. No. 25,841

Term of patent 14 years

Int. Cl. D10—07
U.S. Cl. D42—1

The figure is a plan view of a clock face, showing our new design.

The clock face is conventionally of no appreciable thickness.

We claim:

The ornamental design for a clock face, as shown and described.
